UNITED STATES PATENT OFFICE

134,458

DESIGN FOR AN AIRPLANE

Alfred C. Johnson, San Jose, and Henry W. Funke, Long Beach, Calif.

Application April 17, 1942, Serial No. 106,594

Term of patent 14 years

To all whom it may concern:

Be it known that we, Alfred C. Johnson and Henry W. Funke, citizens of the United States, residing at San Jose and Long Beach, respectively, in the counties of Santa Clara and Los Angeles, respectively, and State of California, have invented a new, original, and ornamental Design for Airplanes, of which the following is a specification, reference being had to the accompanying drawings forming a part thereof.

Fig. 1 of the drawings is a perspective view of an airplane embodying the new design as it would appear from a point off to the side and

slightly forward and above the airplane while the latter would be in flight;

Fig. 2 is a top plan view of the airplane;

Fig. 3 is a front elevational view of the airplane; and

Fig. 4 is a side elevational view of the airplane.

The dominant features of our design reside in the portions shown in full lines in the drawings.

We claim:

The ornamental design for an airplane, substantially as shown and described.

ALFRED C. JOHNSON.
HENRY W. FUNKE.
